UNITED STATES PATENT OFFICE.

JAMES A. DUNN, OF SAUGUS, MASSACHUSETTS.

ARTICLE-HOLDER.

1,313,803.

Specification of Letters Patent. Patented Aug. 19, 1919.

Application filed March 1, 1918. Serial No. 219,753.

To all whom it may concern:

Be it known that I, JAMES A. DUNN, a citizen of the United States, residing at Saugus, in the county of Essex and State of Massachusetts, have invented new and useful Improvements in Article-Holders, of which the following is a specification.

This invention relates to a device for holding articles such as pails of paint and which is adapted to be attached to a ladder and to hold the pail of paint in an upright position irrespective of the inclined position of the ladder. The device is also adapted to be used to hold a quantity of shingles in position to be conveniently used by the carpenter when shingling a roof.

The invention consists in the combination and arrangement of parts set forth in the following specification and particularly pointed out in the claim thereof.

Referring to the drawings:

Figure 1 is a front elevation of a portion of a ladder with my improved device for holding a pail of paint in operative position thereon, the pail of paint being indicated in dotted lines and the ladder being broken away.

Fig. 2 is a side elevation taken from the right of Fig. 1 with the ladder in an inclined position.

Fig. 3 is a plan view of the same with the side rail of the ladder shown in section.

Fig. 4 is a side elevation of a portion of a ladder with my improved article holding device attached thereto and a holder for holding shingles in position when used on a roof in connection therewith.

Fig. 5 is a front elevation of the holder illustrated in Fig. 4.

Fig. 6 is an enlarged plan view of a portion of the device of my invention.

Like numerals refer to like parts throughout the several views of the drawings.

In the drawings, referring to Figs. 1, 2, 3 and 8 is the side rail and 9 the rungs of a ladder. 10 is a bracket having two side portions 11 and 12 which are connected by a cross portion 13, said side portions having a channel 14 therebetween to receive the side rail 8 of a ladder. The bracket 10 is clamped to the side rail 8 by clamp-screws 15 which have screw-threaded engagement with the side portion 11 of the bracket 10 and bear against the side rail 8, forcing it against the side portion 12.

The bracket 10 has a pintle 16 thereon,

the median axial line of which is substantially parallel to the channel 14. An auxiliary bracket 17 is pivoted on the pintle 16 and has a bore 18 which receives a journal 19, said journal having attached thereto and forming a portion thereof an annular arm 20 which is adapted to receive a pail 21 and hold the same in an upright position. The annular arm 20 and the cylindrical hub 19 form together a holder 29 for the pail 21. The median axial line of the journal 19, and consequently of the holder 29, is arranged substantially at right angles to the median axial line of the pintle 16.

The auxiliary bracket 17 is split at 22 and is provided with ears 23 and 24, the ear 24 being screw-threaded to receive a clamp-screw 25 which is provided with a handle 26 shouldered at 27 to bear against the ear 23 and thus clamp the cylindrical journal 19 in the bore 18 of the auxiliary bracket 17. The auxiliary bracket 17 is fastened to the pintle 16 by a set-screw 28.

The operation of the device illustrated in Figs. 1, 2, 3 and 6 is as follows: The ladder being in an inclined position as illustrated in Fig. 2, the clamp-screw 25 is loosened to allow the holder 29 to be set in a horizontal position and said clamp-screw is then tightened to grip the journal 19 in the bore 18 of the auxiliary bracket 17. If it is desired to swing the pail outwardly or inwardly toward the building against which the ladder rests, the set-screw 28 is loosened and the auxiliary bracket is rotated about the pintle 16 until it assumes the desired position, whereupon it is again fastened to the pintle 16 by tightening the clamp-screw 28.

To move the device bodily to different positions on the ladder, the clamp-screws 15 are loosened and when the device has been moved to the desired position on the side rail 8 said clamp-screws are again tightened.

In Figs. 4 and 5 a modified form of holder is illustrated, the device being in all other respects like that hereinbefore described and illustrated in Figs. 1, 2, 3 and 6. Referring, now, to the form of holder illustrated in Figs. 4 and 5, the cylindrical journal 30 has an arm 31 thereon which consists of a cylindrical portion 32 with arms 33 thereon to which is fastened a shelf 34. The journal 30 is inserted in the bore 18 of the auxiliary bracket and is clamped to said auxiliary bracket by means of the handle 26 and

clamp-screw 25. The holder 31 may thus be set as indicated in Fig. 4 or at any desired angle relatively to the side of the ladder and to the roof upon which the ladder rests, 5 thus forming a support for an article, such as a bunch of shingles, to prevent the same from sliding down the roof and to hold the same always in convenient position for the carpenter while he is using the same.

10 Having thus described my invention, what I claim and desire by Letters Patent to secure is:

A device of the character described having, in combination, a bracket having a 15 channel therein adapted to receive one side rail of a ladder, a pintle on said bracket, the median axial line of said pintle being substantially parallel to said channel, an auxiliary bracket pivoted on said pintle and having a bore therein, the median axial line of 20

which extends substantially at a right angle to the median axial line of said pintle, a holder comprising a journal rotatable in said bore, said auxiliary bracket being split longitudinally of said bore and at one side thereof, a clamp-screw having screw-threaded engagement with the split portion of said auxiliary bracket, whereby said split portion may be clamped upon said journal to position said holder thereon, and an annular arm on said journal adapted to receive a container for liquid. 25

In testimony whereof I have hereunto set my hand in presence of two subscribing witnesses.

JAMES A. DUNN.

Witnesses:

CHARLES S. GOODING,
SYDNEY E. TAFT.
